DESIGN FOR A COMB

Siegfried Behr, Flushing, N. Y.

Application March 14, 1940, Serial No. 90,914

Term of patent 3½ years

To all whom it may concern:

Be it known that I, Siegfried Behr, a citizen of the United States, residing at Flushing, county of Queens, State of New York, have invented a new, original, and ornamental Design for a Comb, of which the following is a specification, reference being had to the accompanying drawing, forming part thereof.

Fig. 1 is a plan view of a comb showing my new design.

Fig. 2 is a cross sectional view through the center of the comb.

Both sides of the comb have the same design.

I claim:

The ornamental design for a comb, as shown and described.

SIEGFRIED BEHR.
